UNITED STATES PATENT OFFICE

JOHN P. KOLLA, OF HOLLAND, MICHIGAN, ASSIGNOR TO HOLLAND FURNACE COMPANY, OF HOLLAND, MICHIGAN

RADIATOR FOR WARM-AIR FURNACES

Application filed October 24, 1927. Serial No. 228,246.

This invention relates particularly to improvements in one-piece radiators for warm air furnaces.

The objects of the invention are:

5 First, to provide a one-piece radiator of large capacity and high efficiency in its radiation.

10 Second, to provide such a structure with a safety relief in the event of an explosion within the furnace.

Objects pertaining to details and economies of my invention will definitely appear from the description to follow.

15 I accomplish the objects of my invention by the devices and means described in the following specification. The invention is clearly defined and pointed out in the claims.

20 A device embodying my invention is clearly illustrated in the accompanying drawing forming a part of this application, in which:

Fig. 1 is a detail elevation view of a furnace embodying the features of my invention, the radiator being shown in section on line 1—1 of Fig. 2.

25 Fig. 2 is a detail horizontal sectional view through the radiator, showing its contour, taken on the plane of line 2—2 of Fig. 1.

The parts will be identified by their numerals of reference which are the same in 29 all views.

1 is the usual casing of a furnace. 2 is the upper part of the combustion chamber. 3 is my improved one-piece radiator. It has a central dome 31 around which is a projecting 35 flange 32 forming a joint with the top opening of the said combustion chamber 2. Leading spirally from the central dome 31 is the passage 33 of gradually lessening cross sectional dimension until it emerges at the smoke pipe 40 connection 34, which is contracted slightly downwardly at the discharge end as indicated.

At the front is a vent passage 35 closed by 45 the trap door 36 which is hinged at 37 and rests by gravity against the inclined flange 38, see particularly Fig. 1.

With this construction it will be observed 50 that the combustion gases are delivered upwardly from the combustion chamber into the comparatively large central dome from which 55 they circulate spirally in a spiral passage

diminishing in cross section to the discharge opening which is slightly restricted and slightly lower than the said passage. Also that the smoke discharge connection is supplied with a vent 35 so that in the event of an 55 explosion within the furnace the trap door 36 opens automatically and relieves the pressure.

The structure can be somewhat modified in detail. I desire to claim the same specifically and also broadly as pointed out in the appended claims.

Having thus described my invention what I claim as new and desire to secure by Letters 60 Patent is:

1. In a one-piece radiator for a warm air furnace, the combination of a central dome-like part with flanged joint connecting at the top opening of the combustion chamber, a spiral passage leading from the central dome-like part in spaced relation thereto and with constantly diminishing cross section and with an inclination downwardly to a restricted smoke discharge, a vent passage leading 70 therefrom having an inclined flange opening and having a trap door hinged at its top and resting against said flange, coacting as specified. 75

2. In a one-piece radiator for a warm air furnace, the combination of a central dome-like part with flanged joint connecting at the top opening of the combustion chamber, a spiral passage leading from the central dome-like part in spaced relation thereto with constantly diminishing cross section and with an 80 inclination downwardly to a restricted smoke discharge, coacting as specified. 85

3. In a one-piece radiator for a warm air furnace, the combination of a central dome-like part with flanged joint connecting at the top opening of the combustion chamber, a spiral passage leading from the central dome-like part in spaced relation thereto and with an inclination downwardly to a reduced 90 smoke discharge, coacting as specified. 95

In witness whereof I have hereunto set my hand.

JOHN P. KOLLA.
